UNITED STATES PATENT OFFICE.

LESLIE N. DANIELS, OF OAK PARK, ILLINOIS.

HAT-PROTECTOR.

1,330,582.

Specification of Letters Patent. Patented Feb. 10, 1920.

Application filed November 24, 1916, Serial No. 133,122. Renewed May 5, 1919. Serial No. 295,030.

To all whom it may concern:

Be it known that I, LESLIE N. DANIELS, citizen of the United States, residing at Oak Park, in the county of Cook and State 5 of Illinois, have invented certain new and useful Improvements in Hat-Protectors; and I do hereby declare the following to be a full, clear, and exact description of the invention, such as will enable others skilled in 10 the art to which it appertains to make and use the same.

My invention relates to hat protectors, its prime objects being to provide cheap, effective, neat and easily portable means for 15 protecting head-dress from the weather.

More particularly, my invention aims to provide a hat protector adapted to be stored in a comparatively small space when not in use, and adapted when in use to effectively 20 protect both the hat and the hair of the wearer from rain, sleet, snow, unusually hot sun rays, or other inclemencies of the weather. Further objects of my invention are to provide a device of the class described 25 so arranged as to be normally carried in a pocket, a hand-bag, or even in the crown of a hat; to provide simple and effective means for stiffening the protector when in use and for reducing its effective size according to 30 variations in the size of the hat which it is to protect; to provide means for holding the protector in operative position, and preferably to have such holding means coöperate with the usual hat pins in holding 35 the hat in position also. Still other objects will appear from the accompanying drawings, in which latter—

Figure 1 is a view showing the use of a hat protector embodying my invention.

Fig. 2 is a reduced plan of the blank from 40 which the protector of Fig. 1 was formed and shows a portion of the holding means.

Fig. 3 is a fragmentary view of the protector of Fig. 1, showing one form of stiffening means.

Fig. 4 is a perspective view showing the embodiment of Fig. 1 when folded.

Generally speaking, I accomplish the objects of my invention by forming a sharp 50 tipped roof from a flexible and waterproof material and so joining the roof portions as to prevent gaps, by equipping the sloping sides of the roof with stiffening means extending along said sides toward the tip of 55 the roof, by securing one or more chin bands to the otherwise completed protector,

and by providing means for compacting the finished protector without rupturing either the material in general or the said stiffening means. For example, I may take a blank 1 60 shaped like Fig. 2 and made of waxed paper, oiled paper or cloth, or other flexible and comparatively moisture-impervious sheet material, which blank amounts substantially to a circle from which a sector-shaped portion has been omitted. Upon forming this blank into a conical shape and suitably securing the edge portions of the substantially sector-shaped cut to each other (preferably in some one of the well known manners whereby such materials are adjoined without gapping) I obtain a protector for the purpose mentioned. To hold this in operative position when in use, I preferably attach 70 tying-strings 2 to the inner surface of the 75 hollow cone at points located at some distance above the edge of the cone, thus permitting the protector to be held in place without contracting its periphery. In practice, I preferably start with a blank of such 80 size and shape that the resulting protector will be considerably larger in the diameter of its opening than the ordinary hats, thus causing the protector to act as a roof extending downward beyond the brim of the 85 hat for the better protection of both the hat, hair, collar, etc., of the wearer.

While the material used may vary considerably in weight and texture, I preferably 90 use a rather thin material so as to permit of its easy folding into a quite small compass. Then, since such comparatively thin material might not be sufficiently rigid to withstand the impact of heavy rain or sleet against the edge portions of the protector, I may also provide means for stiffening the 95 protector. For this latter purpose, I may indent the protector with relatively small furrows 4 extending radially of the original blank and inward from the periphery of 100 the latter, as shown in Figs. 2 and 3; or, I may attach stiffening ribs 3 along corresponding lines to the interior of the conical protector as shown through the paper in Fig. 1. In either case, the protector may 105 also be creased to provide lines along which it may readily be folded without cracking or otherwise injuring either the material of which the main element is made, or the stiffening means associated with the latter. 110 The aforesaid lines of fold or creases, or the furrows 4 present elongated inwardly ex-

tending edges which extend radially of the blank and engage the hat at intervals throughout the circumference thereof, preventing crushing of the hat ornaments or 5 trimmings.

It will be obvious from the above that by using a suitable blank and a method of adjoining certain portions of the blank in fixed relations, I obtain a protector having 10 a predetermined general shape, but still permitting a considerable distortion so as to conform to variations in the shape of the hat and the trimmings on the same. Also, that by thus providing a roof-shaped 15 protector with a relatively sharp tip and with a smooth exterior, I avoid non-draining gutters and depressions which would be present in attempting to form a protector from a non-indented blank. Thus, I am able to 20 produce an exceedingly simple, light and effective protector suitable for sale on trains, at news-stands, in theater or hotel corridors, or the like; and sufficiently compact to be readily carried in a pocket, or within the 25 crown of the hat which it is to protect, or to be packed in an envelop for vending the same in a slot machine. However, while I have described an embodiment of my invention in which the upper edge of the roof 30 is contracted substantially to a point, and in which tapes are used as the holding means, I do not wish to be limited to these or other details of the construction and arrangement herein disclosed, it being obvious that the 35 same might be varied in many ways without departing from the spirit of my invention.

I claim as my invention:

1. A hat protector composed of a substantially circular sheet of flexible material having 40 a sector-shaped opening, said sheet being formed into approximately conoidal shape with the edges formed by said opening secured to each other and being provided with a series of stiffening means extending radially of the sheet and at spaced 45 intervals throughout the circumference

thereof, each of said stiffening means terminating in relatively remote spaced relation to the center of the sheet, and a pair of oppositely related radial tying strings secured to the sheet at points spaced from the periphery thereof so as to allow the sheet to be firmly secured without contracting its periphery. 50

2. A hat protector composed of a substantially conoidal shaped member formed of a sheet of flexible material, said member being formed with a series of radial folds at spaced intervals throughout its circumference to provide stiffening means, said 60 folds terminating in remotely spaced relation to the apex of the conoidal member, and fastening strings carried by the member and secured thereto in the spaces between adjacent folds and at points spaced 65 from the periphery of the member so as to allow the latter to be firmly secured without contracting its periphery. 55

3. A hat protector composed of a substantially conoidal shaped member formed 70 of a sheet of flexible material, said member being formed with a series of inwardly extending radial folds at spaced intervals throughout the circumference thereof presenting a series of elongated inwardly extending radial edges to engage the hat at 75 corresponding intervals throughout the circumference thereof.

4. A hat protector composed of a substantially circular sheet of flexible material 80 having a sector shaped opening, said sheet being formed into approximately conical shape with the edges formed by the opening secured to each other, said sheet having radial lines of fold, and a pair of oppositely 85 related radial tying strings secured to the sheet at points spaced from the periphery thereof so as to allow the sheet to be firmly secured without contracting its periphery. 90

Signed at Chicago, November 22nd, 1916.

LESLIE N. DANIELS.
